UNITED STATES PATENT OFFICE.

GEORGE F. VOIGHT, OF OAKLAND, CALIFORNIA.

FURRING PLATE.

Application filed September 15, 1924. Serial No. 737,826.

My invention relates to improvements in furring plates particularly adapted for furring wire lath out a suitable distance from the corners of stucco structures, although 5 also useful for other purposes.

One of the objects of the present invention is the provision of a series of separately attachable furring plates, whereby the plates may be attached to the corners of stucco 10 structures in such spaced apart order as may be best suited to the various lengths of such corners and as may be best suited to the type of wire lath employed;

A further object is the provision of a 15 furring plate formed of a strip of sheet metal and comprising a body portion having portions struck outwardly to form a pair of side wings, and having its front edge bent to the opposite side to form a furring lip;

20 A still further object is the provision of one or more reinforcing indentations or corrugations extending laterally across the plate for providing certain rigidity thereto;

A still further object is the provision of 25 one or more fastening prongs on the plate adapted to be driven into the wood along one side of the corner for attaching the plate thereto;

With the foregoing and still further objects and purposes in view which will appear as the description proceeds, my invention resides in the combination and arrangement of parts and in the details of construction hereinafter described and 35 claimed, it being understood that changes in the precise embodiment of the invention herein disclosed can be made within the scope of what is claimed without departing from the spirit of the invention.

40 In the accompanying drawings—

Figure 1 is a perspective view of a convexed corner formed by the rectangular intersection of two perpendicular walls of a stucco structure, and a number of my improved furring plates attached thereto;

Figure 2 is a front elevation of one of the furring plates;

Figure 3 is a perspective view of one of the plates;

50 Figure 4 is a view on line 4'-4', Fig. 1;

Figure 5 is a view on line 5'-5', Fig. 2;

Figure 6 is a view on line 6'-6', Fig. 2;

Figure 7 is a view on line 7'-7', Fig. 2;

Figure 8 is a view on line 8'-8', Fig. 2;

55 Figure 9 is a view on line 9'-9', Fig. 2; and

Figure 10 is a blank showing in dotted or broken lines where the principal cuts and bends are made in forming the plates, the reinforcing indentations not being outlined. 60

Referring to the drawings in detail, throughout which like reference characters designate like parts:

The numeral 1 designates the apex formed by the rectangular intersection of two perpendicular walls 2, 3, the latter comprising sheathing boards 4, 5, secured to the face of wall studs 6, the sheathing boards forming a base or backing against which is spread stucco composition 7, the latter reinforced by 65 wire fabric or lath 8. The application of the fabric will presently be more fully described.

9 designates my improved furring plates, which are preferably stamped from sheet 75 metal and comprise each, a body portion 10, out of one side of which are struck a pair of side wings 11, a furring lip 12 formed by bending the front edge of the plate in the opposite direction from the 80 wings 11, and a pair of fastening prongs 13 formed by bending the upper and lower corners of the rear end of the body portion at right angles inwardly.

14, 15, are indentation or corrugations 85 struck into the metal for the purpose of increasing its rigidity, and extend laterally across on opposite sides of the furring lip 12 and across the body portion 10 and side wings 9 respectively. 90

To prevent crowding the corrugations 14, 15, are not indicated in Fig. 1 of the drawings.

The body portion 10 and side wings are disposed on opposite sides of the plane of the 95 furring lip 12 and diverge at angles of 45 degrees therefrom (see Fig. 5).

The furring plates 9, the functions of which are to maintain the fabric 8 a predetermined distance outwardly from the 100 apex 1, are disposed in suitable spaced apart order across the latter, with the body portion 10 seated against the face of the wall 4 and the side wings 11 seated against the wall 5, and are permanently secured thereagainst 105 by means of suitable nails 16 driven thereinto through openings 17, 18, provided therefor in said body portion and side wings.

Obviously, only such number of nails need 110 be employed for attaching the plates as may be deemed necessary. I have found in

practice that one nail driven through the body portion and one nail through one of the side wings secure the plate ordinarily very satisfactorily. However, if so desired, a nail may be provided for each of the openings in both the body portion and side wings.

The fastening prongs 13, which are adapted to be driven in the sheathing boards 6, are intended primarily to secure the plate temporarily only and until one or more nails can be driven for permanently securing it, however, if proper care is exercised in applying the fabric the nails may be omitted altogether from the body portion and the fastening prongs alone depended on for securing it to the sheathing boards.

The reinforcing fabric 8 is applied to the sheathing boards 4, 5, after the application 20 of the furring plates, and in securing it it is preferably attached at one end to one of the walls with suitable staples or nails 20 driven through suitable spacing disks 19, and then bending it at right angles across 25 the face of the furring lips 12 and attaching it with like staples and disks to the opposite wall.

The fabric 8 is adapted as a support and reinforcement for the stucco composition 7, 30 and the latter in its application is intended to be spread against the face of the sheathing boards 4, 5, and on and around the fabric 8 and spacing disks 19 and on and against the furring plates.

I claim:

1. A furring plate formed of a piece of sheet metal having parallel side edges, said plate bent transversely a short distance inwardly from one of said side edges and in parallelism therewith, thereby forming a furring lip and a body portion of equal lengths intersecting at an angle of approximately 135 degrees, said body portion having an intermediate portion struck out at 45 right angles to one side, thereby forming a side wing integrally connected to the furring plate at said intersection of the body portion and furring lip, said side wing being substantially shorter than the transverse diameter of said body portion, said lip adapted to receive and support wire lath on its outer edge, said plate having an opening, and a separately applied fastening element projecting through said opening in a 50 wall member for securing the plate thereagainst.

2. A furring plate formed of a strip of sheet metal having parallel side edges of equal lengths, one of said edges bent at an obtuse angle to one side, thereby forming a furring lip and a body portion of equal lengths intersecting at an angle of substantially 135 degrees, a portion of said body portion struck at right angles to one side, thereby forming a side wing integrally

joined at one end to the furring plate at the intersection of said furring lip and body portion, thereby forming an opening in said body portion intermediate the upper and lower edges thereof and extending from said intersection to a point short of its side edge, said side wing and body portion adapted to seat against a support, the free edge of said furring lip adapted to receive and support wire lath, and a plurality of separately applied fastening elements projecting through said plate in a support for securing the plate thereagainst.

3. Means for furring wire fabric, comprising, an integral element formed of sheet 80 metal having a substantially flat body portion adapted to seat against a surface, a furring lip extending along one side edge thereof substantially the length of the body portion, a side wing intermediate the upper 85 and lower edges of the body portion arranged to seat against a surface substantially at right angles with said first named surface, said element having a corrugation extending across from said furring lip to said side 90 wing, and a separately applied fastening element arranged to project through said first named element in one of said surfaces.

4. Means for furring wire fabric from a support, comprising, a substantially flat 95 body portion arranged to seat against said support and having a furring lip extending along one side edge substantially the full length of said body portion, an intermediate portion of the body portion bent flat-wise 100 to one side to form a side wing disposed substantially at a right angle with the body portion, a corrugation extending across from said furring lip to said body portion above said side wing, a corrugation extending 105 across from said lip to said body portion below the side wing, and a fastening nail arranged to project through said means for securing it to said support.

5. Means for furring wire lath, comprising a substantially rectangular body portion formed of sheet metal terminating at one side edge in a furring lip of substantially equal length therewith, an intermediate portion of said body portion struck at substantially right angles to one side to form a side wing, a corrugation extending transversely across said lip to said body portion above said side wing, and a separately applied fastening element arranged to project through said means in a support for binding the means thereagainst.

6. In a furring plate of the character described, a rectangular body portion terminating at one side edge in a furring lip 125 of substantially equal length therewith, intermediate portions of said body portion struck at right angles to one side thereof to form a pair of vertically spaced side wings, the arrangement being such as to form a 130

pair of vertically spaced openings in said body portion intermediate the upper and lower edges thereof, said openings terminating short of the free side edge of said body portion, a corrugation extending transversely across said body portion above said openings, a corrugation extending transversely across said body portion below said open-

ings, and a corrugation extending transversely thereacross between said openings, 10 said corrugations extending transversely across said furring lip.

In testimony of the foregoing being my own, I have hereunto affixed my signature this 10th day of September, 1924.

GEORGE F. VOIGHT.
